UNITED STATES PATENT OFFICE.

JESSE TAYLOR, OF SALT LAKE CITY, UTAH.

DESIGN FOR A JEWELRY-MOUNTING.

SPECIFICATION forming part of Design No. 35,133, dated October 1, 1901.

Application filed September 7, 1901. Serial No. 74,703. Term of patent 3½ years.

To all whom it may concern:

Be it known that I, JESSE TAYLOR, a citizen of the United States, residing at Salt Lake City, in the county of Salt Lake and State of Utah, have invented and produced a new and original Design for a Jewelry-Mounting, of which the following is a specification.

This invention relates to a new and useful design for a jewelry-mounting, particularly adapted for elk's-tooth charms, and the essential features reside in the design as illustrated in the accompanying drawings, wherein—

Figure 1 is a perspective view of a mounting embodying the design. Fig. 2 is a longitudinal vertical section of the same. Fig. 3 is a transverse vertical section.

The design is characterized by a flat bell-

shaped body having opposite flat parallel sides 1, an upper circular end 2, and side edges 3, with lower outward flares 4. The mounting is hollow and open at the bottom, and the upper end and side edges are rounded in cross-section.

Having thus described the invention, what is claimed as new is—

The design for a jewelry-mounting, as herein shown and described.

In testimony that I claim the foregoing as my own I have hereto affixed my signature in the presence of two witnesses.

JESSE TAYLOR.

Witnesses:

L. MOTH IVERSEN,
JESSE F. CANNON.
